CLAIM

We claim the ornamental design for a wall mount showerhead, as shown and described.

DESCRIPTION

FIG. 1 is a front isometric view of a wall mount showerhead. FIG. 2 is a rear isometric view of the wall mount showerhead of FIG. 1.

FIG. 3 is a front elevation view of the wall mount showerhead of FIG. 1.

FIG. 4 is a rear elevation of the wall mount showerhead of FIG. 1.

FIG. 5 is a top plan view of the wall mount showerhead of FIG. 1.

FIG. 6 is a bottom plan view of the wall mount showerhead of FIG. 1.

FIG. 7 is a left-side elevation view of the wall mount showerhead of FIG. 1; and,

FIG. 8 is a right-side elevation view of the wall mount showerhead of FIG. 1.

The broken lines, which define the bounds of the claimed design, form no part of the claimed design.
